(57) CLAIM

The ornamental design for a container with a mirror surface for interdental brushes, as shown and described.

DESCRIPTION

FIG. 1 is a front perspective view of a container with a mirror surface for interdental brushes, showing my new design;

FIG. 2 is top plan view of FIG. 1;

FIG. 3 is a front edge view of FIG. 1;

FIG. 4 is a left edge of FIG. 1;

FIG. 5 is a bottom plan view of FIG. 1;

FIG. 6 is a rear edge view of FIG. 1; and

FIG. 7 is front perspective view, showing the top lid in the open position; and,

FIG. 8 is a top plan view of FIG. 7.
